UNITED STATES PATENT OFFICE.

HANS PETER KARL THEODOR NIELSEN, OF COPENHAGEN, DENMARK.

PROCESS FOR MANUFACTURING PEAT FUEL.

1,317,936.

Specification of Letters Patent.

Patented Oct. 7, 1919.

No Drawing.

Application filed April 2, 1919. Serial No. 287,059.

To all whom it may concern:

Be it known that I, HANS PETER KARL THEODOR NIELSEN, citizen of the Kingdom of Denmark, residing at Copenhagen, Denmark, have invented new and useful Improvements in Processes for Manufacturing Peat Fuel, of which the following is a specification.

The present invention relates to a process for manufacturing a firm, hard and practically dry fuel from raw peat-mass, without briquetting the same.

The process consists in the raw peat-mass being submitted to so-called wet grinding in a mill, preferably a ball-mill or tube-mill, whereby it is comminuted so far that not only the fibrous texture of the peat but also the cellular structure of the peat fibers have practically disappeared, the cells being torn asunder. Then the water is allowed to run from the peat mass and, the latter is then subjected to pressure whereby it may be molded into the shape of blocks or the like. If necessary, the mass may be further dried by any suitable means, either before or after the molding. Before grinding the raw mass, it may be necessary to add some water thereto, in order to give it a suitable mushy or porridge-like consistency.

It has been demonstrated that, after the here mentioned thorough grinding, the peat-

mass very willingly releases practically its entire contents of water, without the use of artificial means of separation, so that pieces as large as small briquets having contained, 35 after the grinding, as much as about 85% of water would contain, after only a few days of drying in the air, not more than 10 to 15% of water, in which state of dryness the peat would be of firm consistency 40 and form an excellent fuel.

Having now particularly described and ascertained my said invention and the manner in which the same is to be performed, I declare that what I claim is:—

A process for the production of peat fuel from raw peat-mass, characterized by grinding the latter while of the consistency of mush by the pounding and abrasive action of balls, as in the so-called ball mill, until 50 the cell structure has been disintegrated, so that the water is liberated and permitted to run from the mass, and after the material is thus partially dried, subjecting the mass to pressure.

In witness whereof I have hereunto signed my name in the presence of two subscribing witnesses.

HANS PETER KARL THEODOR NIELSEN.

Witnesses:

JULIUS LIBMANN,
CARL HEMMINGSEN.
